CLAIM

The ornamental design for a lighting fixture, as shown and described.

DESCRIPTION

FIG. 1 is a perspective view of a first embodiment of a lighting fixture comprising the new design;

FIG. 2 is a front elevational view thereof;

FIG. 3 is a right side elevational view thereof, a left side elevational view being a mirror image thereof;

FIG. 4 is bottom view thereof;

FIG. 5 is a perspective view of a second embodiment of lighting fixture comprising the new design having a translucent layer behind the circles;

FIG. 6 is a front elevational view thereof;

FIG. 7 is a right side elevational view thereof, a left side elevational view being a mirror image thereof; and,

FIG. 8 is bottom view thereof.

The showing of circles in FIG. 5 extends along the front as shown in FIG. 6.

The broken lines in the figures are for illustration purposes only and form no part of the claimed invention.
